UNITED STATES PATENT OFFICE.

EUGENE L. RICHARDS, OF LITCHFIELD, CONNECTICUT.

HEADLIGHT FOR HORSES.

No. 878,898.

Specification of Letters Patent.

Patented Feb. 11, 1908.

Application filed April 17, 1906. Serial No. 312,136.

To all whom it may concern:

Be it known that I, EUGENE L. RICHARDS, a citizen of the United States, residing in Litchfield, in the county of Litchfield and 5 State of Connecticut, have invented certain new and useful Improvements in Headlights for Horses, of which the following is a specification.

This invention relates to a device whereby 10 a light may be carried by a horse in such a manner that the rays from the light will illuminate the path and will not be obstructed by any part of the body of the horse, and whereby the light will be carried in the most 15 steady manner.

In the drawings accompanying and forming a part of this specification, Figure 1 is a side view of the fore part of a horse shown equipped with a form of my present improvement. Fig. 2 is a perspective view of the device removed from the horse, the strap for preventing the forward movement of the device when in position is not illustrated in this view. Fig. 3 is a side view of the device.

25 It has been attempted from time to time to provide means for carrying a lamp so that the rays of light will fall directly in front of the horse, as for instance by fastening it to the breast collar or shafts; but it has been 30 found that a very great amount of motion and jarring was imparted to the lamp when carried in such positions. I have discovered however, that when a horse is traveling that its neck remains more steady than any other 35 portion of the body, and it is to the neck that I purpose attaching my lamp carrying device which in the present instance is shown as embodying a plate 5 for resting upon the top of the neck 6 of the horse. This plate may be

40 made of sheet metal and of such a length that it will afford a considerable bearing surface upon the neck of the horse to prevent cutting into the flesh or abrading and marring the mane. This plate being made of sheet metal 45 may be readily formed to the various shaped necks of horses to which it may be applied. The edges may be curled up or otherwise reinforced, as at 7, and carry suitable means for the attachment of straps 8 in the present 50 instance loops 9.

The straps are shown as provided with snap hooks 10 for the more ready attachment and detachment of the device from the horse, although the straps are provided with 55 buckles 11 for their adjustment, and which

may in some instances be employed instead of the snap hooks for fastening and unfastening the device on a horse's neck. The lower ends 12 of the straps are fastened to the lower supporting member 13 which will engage the 60 lower side of a horse's neck. This lower or lamp supporting member or plate may be made of some material of suitable characteristics; leather of some stiffness may be employed, since this will be stiff enough to 65 maintain the shape of the device although permitting it to yield to the movement of the neck of the horse, as well as adapting it for conformation to the various thicknesses of necks when it is desired to use the device 70 some times upon one and some times upon another of a number of horses. This plate or member may be perforated as at 14 for purposes of ventilation.

The lamp 15 is shown adjustably carried 75 by a bracket 16, there being a suitable set screw 17 for the adjustment of the lamp upon the bracket. The bracket is carried by a hanger 28, there being an eye 18 on the bracket embracing a set screw 19 which 80 passes through the dependent ears 20, the eye 18 being secured between said ears which are carried by a plate 21, which may be suitably riveted to the supporting member 13, and may be substantially of the same 85 length as such supporting member. Various positions of adjustment are indicated in Fig. 1 by the dotted line positions 22 and 23, the full line position 24 indicating the bracket in substantially a vertical position, 90 and the other positions indicating the lamp in such position that it will throw a light farther forward or cause its rays to be focused upon the ground more nearly in front of a horse's feet. The adjustment not only permits the regulation as to where the light 95 shall be placed, but also permits adjustment to accommodate the device to the angle at which various horses may carry their necks.

To prevent the device slipping forward on 100 the horse's neck, particularly when he is un-checked and drops his head, a strap 25 may be secured to the rearmost loops 9 and be passed over the check rein hook 26 carried by the harness saddle 27. The strap 25 105 may also be provided with a snap hook 30, so that the device may be readily removed by merely unfastening the snap hooks.

This device is readily applied to the horse when occasion may demand, and may be 110

readily removed, and will when in position fit the neck securely but not uncomfortably, and hold the lamp from vibration.

Having described my invention I claim:

- 5 1. The combination of means adapted to closely embrace the neck of a horse, and a 30 swingingly adjustable light pendent therefrom but rigidly connected thereto.
- 10 2. The combination of means adapted to closely embrace the neck of a horse and comprising a rigid member and a flexible member detachably connected one to the other, and a light pendent from the flexible member but rigidly connected thereto.
- 15 3. The combination of a pair of separable strap connected neck embracing members, one to embrace the upper and the other the underside of a horse's neck in such a manner as not to partake of the movement 40 of the shoulders of the horse, and a light pendent from but rigidly connected to the lower of said members.
- 20 4. The combination of a pair of separable strap connected neck embracing members, one to embrace the upper and the other the under side of a horse's neck in such a manner as not to partake of the movement of 45 the shoulders of the horse, and an adjustable

light pendent from but rigidly connected to the lower of said members.

5. The combination with a sheet metal plate for engaging the upper side of a horse's neck, a flexible plate for engaging the lower side of the horse's neck, flexible connection between these, and a lamp bracket carried 35 by the lower plate.

6. In a device of the character specified, the combination with a sheet metal plate conforming to the shape of the upper portion of a horse's neck and having loops, a 40 flexible plate for engaging the lower portion of the horse's neck and shaped to conform thereto, straps carried by the flexible plate, means for connecting said straps to the metal plate, an inflexible plate secured to 45 the central portion of the flexible plate and being of substantially the same length thereof, a pair of ears carried by said inflexible plate, a set screw traversing said ears, a lamp bracket having an eye located between 50 said ears and embracing said set screw, and a lamp adjustably carried by said bracket.
